UNITED STATES PATENT OFFICE.

EDDY T. MCKAIG, OF CHICAGO, ILLINOIS.

DESIGN FOR A METAL BED END.

SPECIFICATION forming part of Design No. 25,996, dated September 8, 1896.

Application filed March 7, 1896. Serial No. 679,659. Term of patent 31 years.

To all whom it may concern:

Be it known that I, EDDY T. MCKAIG, a citizen of the United States, residing at Chicago, county of Cook, State of Illinois, have 5 invented a certain new and useful Improvement in a Design for Metal Bed Ends; and I declare the following to be a full, clear, and exact description of the same, such as will enable others skilled in the art to which it 10 pertains to make and use the same, reference being had to the accompanying drawing, which forms a part of this specification.

My invention has for its object the production of a design for a metal bed end—that 15 is, the head-board or foot-board; and it consists of an arrangement of the parts to produce the design, as hereinafter explained.

The figure in the drawing is a perspective view of the end of a metal bed, as the head-board or foot-board, embodying my invention.

In carrying out the invention B is my end piece. It is made up of upright corner-posts C C', having balls c on the upper ends and hav-

ing horizontal portions D D'. Extending vertically from one horizontal piece, D, to the other, D', is a series of vertical rods or pieces E, each provided on the top with a ball e. Located substantially in the center of the end piece as a whole is a representation of a lyre, as at F. On the top portion D is a scrollwork consisting of a circular piece G and side pieces G'. It is obvious that the pieces D D' may be bow-shaped, as shown, or, if desired, they may be straight. So, also, the scroll G G', being a separate feature of 35 the design, may or may not be employed with the lyre-shaped figure.

What I claim is—

The design for a metal bed end substantially as herein shown and described. 40

In testimony whereof I sign this specification in the presence of two witnesses.

EDDY T. MCKAIG.
